LAMP SEALING MACHINE HEAD

James E. Nelson, Stephen Bosworth, and William Percy, Toronto, Ontario, Frank Balne, Bronte, Ontario, and Arthur Holman, Toronto, Ontario, Canada, assignors to General Electric Company, a corporation of New York

Application October 12, 1944, Serial No. 558,380
In Canada December 15, 1943

3 Claims. (Cl. 49—2)

1

Our invention relates to lamp sealing machines and particularly to machines for sealing double-ended tubular lamps.

In the manufacture of double-ended tubular lamps such as the fluorescent lamps now on the market a preformed mount consisting of an electrode with its lead wires sealed in a glass stem having a flare of a diameter approximating that of a glass tube to which it is to be sealed, is sealed by fusion in each end of an elongated tube, and a contact carrying base is applied to each end.

In operation the based lamps are detachably mounted between spaced fixed contacts and it is therefore important that their overall length be uniform so that they are interchangeable in standard fixtures. It is also desirable that as great a proportion of the space occupied by the lamp be occupied by the luminous tube and as small a proportion as possible occupied by the bases. To this end small flat bases are fitted over the sealed ends of the tube and it is therefore desirable that the seals be uniformly shaped and the overall length of the sealed tube be standard so that the bases may be accurately fitted thereto to give the correct overall length of the lamp.

It is an object of our invention to provide apparatus for the fusing of the flared glass stems supporting electrodes into the ends of the lamp tube in a ready and economical manner at high speed.

Another object of our invention is to provide apparatus for sealing the glass stems to the bulbs so that the sealed portions are properly shaped and dimensioned so that bases may be attached thereto to give the desired overall length of lamp.

Another object of our invention is to provide a sealing head which may be easily loaded and unloaded by the operator, which firmly holds the lamp in position during shaping operation on the seal, and which is adapted to form uniform seals from commercial stems and bulbs which may vary slightly in form from one another.

Other objects and advantages will appear from the following detailed description with accompanying drawings of a specific form of our invention. In the drawings Fig. 1 is a plan view, partially broken away, of a sealing machine embodying my invention; Fig. 2 is a vertical section on a larger scale than Fig. 1 through one of the heads of the machine with parts in position to be sealed; Fig. 3 is a fragmentary vertical section of the head of the supporting spindle; Figs. 4, 5 and 6 are detailed views of parts of the mechanism; and Figs. 7, 8 and 9 are views of the bulb gripping portion of a sealing head.

The apparatus shown in Fig. 1 comprises six-

2

teen heads 11 equally spaced about the periphery of the turret 12 and rotatively mounted therein. The turret 12 is indexed to move intermittently in a counterclockwise direction in a manner well known in lamp sealing machines, so that each head occupies successively for a predetermined period each of the sixteen work stations indicated by the letters A to Q. The rotation of the heads is accomplished by a belt drive. A belt 60 is driven continuously by a mechanism generally indicated at 61 and which may derive its power from the main drive of the lamp machine. The belt 60 engages grooved pulleys 14 (shown in Fig. 2) at the bottom of the heads. All the heads except those located at stations A and B are engaged by the belt 60 and consequently all the heads are continuously rotated individually during operation of the machine except when they are at stations A and B where they are disengaged from the belt 60 and when they are at stations J and K where mechanism is provided to hold them against rotation.

The general sequence of operation of the machine will now be described. An operator is stationed opposite stations A and B and a second operator is stationed opposite stations J and K. These are the loading and unloading stations where the heads are not rotating. At station B the operator places a flared mount which is similar to the mount 51 shown in Fig. 3 except that the exhaust tube 65 is absent, in the head then at the station, and then places on the flared mount a glass lamp tube 50 which assumes a position with respect thereto as shown in Fig. 2. The tube 50 is firmly held in this position by a suction holder 23 engaging the side wall of the tube. At the next station C the parts are pre-heated by suitable fires such as shown at 52 opposite station C. At stations D, E, F and G hard sealing fires 53 such as diagrammatically shown in Fig. 1 opposite these stations are directed at the seals. At the three sealing positions E, F and G suitable mechanism to be later described operates on the seal to shape and locate it. Station H is an annealing position where suitable fires diagrammatically shown at 57 are applied to give a controlled rate of cooling. At station J rotation of the sealing head is stopped in a predetermined position convenient for the operator by mechanism indicated at 59 which holds it against rotation while the head occupies both stations J and K. The operator opposite stations J and K removes the lamp tube 50 with the mount sealed thereto, places a flared mount 51, such as shown in Fig. 3 with the exhaust tube 65, in

the head, reverses the lamp tube and places it in the holder 23 with its open end in sealing relation to the flare 51, as shown in Fig. 2. The head is then stepped through a series of positions L to Q which the same series of operations performed at stations C to H and are carried out to seal this end of the tube. L is a preheating station similar to station C and at stations M, N, O, P the seal is completed in the same manner as at stations D, E, F and G. Station Q is an annealing station similar to station H. At stations A and B the heads encounter a mechanism 59' which is a duplicate of mechanism 59 at stations J and K, whereby rotation of the head is stopped in a predetermined position to facilitate loading and unloading. The completely sealed lamp is removed at station A and the head is ready for reloading.

Referring particularly to Fig. 2 for a description of the sealing head, each head 11 has a sleeve 13 rotatively mounted in a bearing 64 in the turret 12. The sleeve 13 carries at its lower end a grooved driving sheave 14. A spindle having a mount pin 19 with an enlargement or head 20 at its upper end is mounted axially of the head in a manner whereby it rotates with the head but can be moved longitudinally during rotation. This spindle comprises three parts, a rod 15 extending axially of the sleeve 13, a hollow section 18 having its lower end detachably fitted in a socket 17 at the upper end of the rod 15, and an upper section constituting a mount pin 19 having the enlargement or head 20. The upper surface of the mid-portion of the pin head 20 is of conical shape approximately conforming to the shape of the flare portion of mount 51. The lower end of the socket part 17 of rod 15 rests on the upper surface of the head 11 thereby defining the downward limit of movement of the rod and consequently the vertical position of the flare mount pin head 20. The lower end of the rod 15 carries an enlargement 16 constituting a tappet to be engaged by mechanism (to be later described) for the purpose of raising the spindle. The pin 19 is proportioned to loosely fit in the section 18 and its enlargement or head 20 is hollow, and so shaped that the exhaust stem 65 and the lead wires 66 may be loosely accommodated therein to permit the flared mount 51 to rest on the support with some amount of lateral adjustment thereon. Projecting upwardly from a boss 21 on the head 11 is a hollow support rod 22 carrying at its upper end a lamp holder 23 equipped with a valve 34. A passageway 25 drilled in the boss 21 establishes communication between the bore of support rod 22 and the annular space 26 between the rod 15 and the central part of the sleeve 13 which is of enlarged internal diameter at this point. An opening 27 in the sleeve 13 establishes communication with an annular chamber 28 provided in the bearing 64. Connection of the chamber 28 with an exhaust system is made by means of a pipe 29. It will be apparent from the construction just described that communication between the hollow stem 22 and the pipe 29 exists during rotation of the head 11 in its bearing.

The construction of the suction holder 23 will be best seen by reference to Figs. 7, 8, and 9. The holder 23 carries a gripping portion 30 having the shape of a longitudinal section of a cylinder of the same diameter as the tubular bulb to be held. A rubber gasket 31 surrounds the edge of the forward face of the grip 30 defining a suction chamber 32. A cylindrical slide valve

34 having operating buttons 35 and 36, one at each end, is arranged to be reciprocated in a cylindrical bore 34 extending transversely of the holder 23, its movement being guided and limited by a stop pin 37 thereon engaging in a groove 38 in the holder. Interconnected passageways are provided in the slide valve 34 and in the holder 23 in a well-known manner at positions such that when the slide 34 is moved to the position shown in Figs. 7 and 9 and also in Fig. 2, the chamber 32 is in communication with the hollow support 22 and consequently with the exhaust system. When the slide valve 34 is moved to its other extreme position illustrated by Fig. 8 the exhaust system is closed off from the chamber 32 and communication is established between the chamber 32 and the atmosphere. To this end the valve 34 is provided with a right angle passage 36 (Fig. 2) which, when the valve is in the position shown in Figs. 2, 7 and 9, joins the passages 37, 38 (Fig. 2) in the holder 23, thereby connecting the chamber 32 with the interior of support 22 and thence through opening 39 in support 22 with passage 25 in boss 21, passage 30 in head 11, aperture 31 in sleeve 13, annular space 26, opening 27, annular chamber 28 and pipe 29.

To load a head 11 the operator places a flared mount 51 on the mount support 20 in the position shown in Fig. 3. The lamp tube 50 is then placed with its end engaging the flare 51 as shown in Fig. 3 and the body of the tube is pressed against the gasket 31. The operator may use a finger of the hand pressing the tube in position on holder 23 to engage the button 35 and push the slide valve 34 to the position indicated in Fig. 9 whereby connection to the exhaust system is made and the tube is firmly held by suction in the desired position. The loose fit of the mount 51 on the support 20 permits a self alignment of the parts to be sealed and permits the proper relative location of the parts 50 and 51 to be sealed regardless of slight discrepancies in the size of the parts such as eccentricity of the tube 50.

The holding apparatus described permits easy and quick assembly of the tube 50 in a definite position on the head 11 by the operator who places it against the holder 23 with one hand and operates the valve to secure it in position by suction, with a finger of the same hand. The tube 50 is firmly held so that it retains its original position during subsequent operations on its lower end during sealing as will be later described. Similarly the sealed tube may be readily unloaded by the operator with one hand by grasping the tube opposite the holder 23 in such a manner that a finger engages the button 36 of the valve 34 to slide it to the position where connection with the exhaust is broken and the lamp released. Further the support 20 as described permits some latitude of movement of the flare 51 thereon whereby the flare is self-adjusting to centre with the end of the tube in sealing position in such a manner that it accommodates the parts with considerable tolerance of size and shape of the parts such as is encountered in their commercial manufacture at high speed.

When the head moves from position B it is released from holding mechanism 59' and its driving sheave 14 comes into engagement with the belt 60 which causes it to rotate. At position C the glass parts are subjected to suitable fires indicated at 52 whereby their temperature is raised towards the fusing point. At position D harder

fires are concentrated at the seal to raise them to a temperature approaching fusion. At station E the seal is fused by further sealing fires 53. In this position mechanism generally indicated at 55 in Fig. 1 and shown in detail in Fig. 4 engages beneath the tappet 16 of the reciprocable spindle 15. This mechanism consists of an arm 41 pivoted at 42 in a bracket 46 mounted on stationary base plate 40 of the machine. One end of the arm carries the counterweight 43 and the other end a roller 44 which is pressed against the tappet 16 by the counterweight. An adjustable stop 45 bears against the bracket 46 and determines the upper limit of movement of the roller 44. As the meeting edges of the flare 51 and the bulb 50 become fused they are pressed upwardly a distance determined by the setting of the stop 45 and are tacked together to form a seal, the bulb 50 being firmly held by the suction grip 23. When the head moves from the position E it clears the mechanism 55 and the spindle drops to its normal position. In this position the seal is spaced from the support 20, and the sealing fires at the next position F can unobstructedly impinge on it, and heat is not abstracted from the fused parts by conduction through the metal support.

The seal further fused at station F tends to sag somewhat from the position to which it was elevated at station E by mechanism 55. Immediately after the head leaves station F in its travel towards station G it encounters mechanism 56 shown in detail in Fig. 5 whereby the spindle is bumped up a predetermined amount. The mechanism 56 consists of a roller 70 mounted on a bracket 71 secured to the stationary plate 40 in the path of movement of the tappet 16. The engagement of the tappet 16 by the roller 70 bumps up the spindle and consequently presses upwardly on the seal. When the head has passed the mechanism 56 the spindle drops to its normal position whereby it is spaced from the seal and the sealing fires 53 at the next station G are most effectively employed as described in connection with station F. When the head leaves station G it engages mechanism 76 shown in dotted lines in Fig. 1 and in detail on an enlarged scale in Fig. 6. This mechanism consists of a track 76 supported a predetermined distance above the base plate 40 in the path of movement of the tappet 16.

As the tappet 16 rides up the beveled end 74 of track 76 the spindle is elevated to press upwardly on the seal and is maintained in this elevated position during its travel to the next station H. This is an annealing station where the rate of cooling of the seal is controlled by suitable fires indicated at 57. The supporting track 76 to support the seal is provided at this point for the reason that the flare sealed in the tube as described is loosely positioned in the support 20 and the lead wires accommodated in its central bore. The lead wires are somewhat resilient and if the softened glass of the seal as finally formed at station G and by cam surface 74, is not supported until the seal has time to harden somewhat they are liable to tip the flare with the result that a distorted seal is formed.

It has been described that at the station E and on leaving the stations F and G the glass as softened at these stations is pressed upwardly a predetermined amount to bring the seal to form. It is preferable that the height to which the seal is pressed should be slightly greater successively at these stations.

When the head moves from the annealing position H, mechanism 59 is provided whereby ro-

tation of the head is stopped in a position which is most convenient for the operator in unloading and to hold it in this position against rotation so that it may be conveniently loaded. This mechanism is best shown in Fig. 1 and comprises a spring bar 75 pivoted at 76' on a bracket 77 secured to the stationary base plate 40 of the machine. The free end of the spring bar is engaged by a dog 78 rotatively supported on the base plate 40 and spring biased by a torsion spring to the position shown in Fig. 1. The individual heads 11 have a rotation in a clockwise direction as viewed in Fig. 1 so that when a pin 81 projecting upwardly from the pulley 14 of the head comes in contact with the bar 75, rotation of the head is stopped. As the pin 81 is secured on the pulley 14 in predetermined relation to the position of the suction holder 23 the rotation is stopped with the holder 23 lying in the most advantageous position to permit unloading of the lamp with the first seal complete and the reloading of the head. As the head travels from station J to station K it is held against rotation by the belt by reason of the fact that the pin 81 slides 20 along the bar 75 which is sufficiently resilient to permit this movement. If it should happen that the pin 81 was in a position such that it engages the bar 75 head on when it first makes contact, the spring biased dog 78 will give to an amount 25 sufficient to permit the head to continue its rotation and to be stopped in the desired position when the pin next engages the bar.

At station J the tube 50 with the seal completed at one end is removed by the operator. At station K a flared mount 51 such as shown in Fig. 3 with exhaust tube 65 is placed in the head 20, the tube 50 is inverted and its end 63 placed on the flare in the same manner as described for loading at station B. The stations L to Q inclusive correspond to the stations C to H whereby the seal at the other end of lamp is completed and delivered to unloading station A. To this end a duplicate (not shown) of mechanism 55 is provided at station N, and station O is provided with mechanism 56' which is a duplicate of mechanism 56 at station F. Also, a preheat burner 52' is located at station L, fusing burners 53' at stations M, N, O, P, and an annealing burner 57' at station Q. In this case, however, the mechanism for raising the spindle head as it leaves the last sealing fires P is illustrated as mechanism 56'' similar to mechanism 56 and 56' used at stations F and O. As the flare mount for sealing the second end of the tube has the exhaust tube 65 extending well down into the bore of the spindle 19 the flare is supported by it against tipping in the manner described with respect to station H, and the support mechanism of Fig. 6 used between stations G and H is, therefore not required between stations P and Q, though it may be used if desired.

The apparatus described permits easy and rapid loading of the parts in the heads and is adapted for high speed operation. The arrangement provided for fusing and uniting the parts and working the seal to its final form results in uniformly shaped and positioned seals, so that overall length of sealed lamps is uniform and so that the bases may be readily and uniformly applied to give uniform length of completed lamp.

While we have shown and described a preferred embodiment of our invention, it will be obvious to those skilled in the art that various substitutions, modifications or omissions may be made

therein without departing from the spirit of our invention.

What we claim as new and desire to secure by Letters Patent of the United States is:

1. Apparatus for sealing mounts in elongated lamp tubes comprising a sealing head having a mount supporting spindle, a standard projecting upward from the head and carrying a suction chamber shaped to engage the side of the lamp tube, a passageway leading from said suction chamber through the head to an exhaust system, a valve in said passageway adjacent the suction chamber. 5

2. Apparatus for sealing mounts in elongated lamp tubes comprising a sealing head having a mount supporting spindle, a standard projecting upward from the head and carrying a suction chamber shaped to engage the side of the lamp tube, a passageway leading from said suction chamber through the head to an exhaust system, a reciprocable valve in said passageway adjacent the suction chamber, said valve constructed and arranged to be engageable by the fingers of the hand of an operator holding a lamp tube on said suction chamber. 15

3. Apparatus for sealing mounts in elongated lamp tubes comprising a sealing head having a mount supporting spindle, a standard projecting upward from the head and carrying a suction chamber shaped to engage the side of the lamp 20

25 tube, a passageway leading from said suction chamber through the head to an exhaust system, a reciprocable valve in said passageway, said valve located immediately in the rear of the suction chamber and lying transverse thereto whereby it is readily engaged by the fingers of a hand applying a tube to the suction chamber.
